CLAIM

The ornamental design for a heating device for atomizer, as shown and described.

DESCRIPTION

FIG. 1 is a front elevation view of a heating device for atomizer;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a perspective view thereof; and,

FIG. 8 is another perspective view thereof.

The stippled portions shown in the drawings indicate a contrast in material, specifically ceramic material.
